(57) **CLAIM**

The ornamental design for a portable bat rack with under flange for insertion into a common paint or spackle can, as shown and described.

DESCRIPTION

FIG. 1 is a top plan view of a portable bat rack with under flange for insertion into a common paint or spackle can showing my new design;

FIG. 2 is a front elevational view thereof, the rear and sides adjacent being identical in appearance;

FIG. 3 is a bottom plan view thereof; and,

FIG. 4 is a top perspective thereof, with the broken-line disclosure of baseball bats and a spackle can being for illustrative purposes only and forming no part of the claimed design.
